UNITED STATES PATENT OFFICE.

FRED DE MIER, OF PICHER, OKLAHOMA.

ORE JIG.

1,420,975.

Specification of Letters Patent. Patented June 27, 1922.

Application filed July 6, 1921. Serial No. 482,700.

To all whom it may concern:

Be it known that I, FRED DE MIER, a citizen of the United States, and a resident of Picher, in the county of Ottawa and State 5 of Oklahoma, have invented certain new and useful Improvements in Ore Jigs, of which the following is a specification.

My invention relates to jigs for recovering ore and a purpose of my invention is 10 the provision of a jig which eliminates the employment of water as a separating medium and the resultant ore losses, and provides mechanical means therefor unaided by water.

15 It is also a purpose of my invention to provide a jig in which the screened bottoms of the cells are all on one and the same level, and which includes a plurality of rakes mounted for curvilinear movements in the 20 cells and simultaneously by a single actuating means to effect the successive raking of the material from one cell to the other throughout the series.

I will describe one form of jig embodying 25 my invention, and will then point out the novel features thereof in claims.

In the accompanying drawings:

Figure 1 is a view showing in side elevation one form of jig embodying my invention. 30

Figure 2 is a top plan view of the jig shown in Figure 1.

Figure 3 is an enlarged detail perspective view of a portion of the raking member and 35 adjacent mechanism.

Figure 4 is a view showing in end elevation the jig shown in Figures 1 and 2.

Figure 5 is a transverse sectional view taken on the line 5—5 of Figure 1.

40 Figure 6 is a longitudinal sectional view taken on the line 6—6 of Figure 4.

Similar reference characters refer to similar parts in each of the several views.

Referring specifically to the drawings, my 45 invention in its present embodiment comprises a tank designated at T and which in the present instance is of rectangular formation as shown in Figure 2. This tank is provided with a dividing wall 15 arranged 50 longitudinally thereof at a point medially between the sides of the tank in the manner clearly shown in Figure 5. This wall 15 divides the tank longitudinally into a plunger section 16 and a separating section 17.

55 The bottom of both sections 16 and 17 is defined by a wall 18 which is inclined from

the plunger section downwardly to the separating section, thus serving to deflect the water and ore downwardly in the direction of a plurality of outlet ports 19 controlled 60 by faucets 20.

As clearly shown in Figures 2 and 5, the plunger section is divided into a plurality of compartments by partitions 21 arranged transversely and at regular intervals 65 along the length of the section. Supported upon each partition 21 is a bearing 22 in all of which is journaled a shaft 23 adapted to be driven by a pulley 24 about which is trained a belt 25 connected to some suitable 70 source of power (not shown). Fixed eccentrically and at regular intervals on the shaft 23 are cams 26, one for each of the compartments. Loosely embracing each cam is a split ring 27 provided with a yoke 28 to 75 which is connected the rod 29 of a plunger 30. The opposite end of the rod 29 is connected to the plunger 30 through the medium of a yoke 31 as is clearly shown in Figure 5. The plunger 30 is adapted to be 80 reciprocated vertically within the corresponding compartment when the shaft 23 is rotated, it being understood that the cam 26 rotates within the ring 27 to effect reciprocation of the rod 29. As all of the cams are 85 fixed to the same shaft, it will be clear that simultaneous movement of all of the plungers is effected when the shaft 23 is rotated.

Water is adapted to be supplied uniformly 90 to all of the compartments from a trough 32 arranged at one side of the tank and communicating with the compartments through inlet ports 33 in a manner clearly shown in Figures 2 and 5.

The separating section 17 is divided along 95 its length into a plurality of compartments by means of partitions 34, such partitions being a continuation of the partitions 21 as will be clearly seen by an observation of Figure 5. Within each compartment adjacent its upper end is horizontally arranged a screen 35, and as clearly shown in Figure 6, the several screens of all of the compartments are disposed in one and the same plane. That portion of each compartment 100 above the screen constitutes a cell as designated at 36 in which is adapted to work a rake composed of a plurality of perforated angle bars 37. The bars of all of the rakes are sustained on a pair of channel bars 38 105 mounted for vertical swinging movement by means of rocker arms 39 slidably fitted on

yokes 40 fixed to the channel bars, with the rocker arms keyed to a cam shaft 41 journaled in bearings 42. An actuating rocker arm 43 is also keyed to a shaft 41 as clearly shown in Figure 2, and this rocker arm is adapted to be lifted to cause oscillation of the shaft by means of a lever 44 fulcrumed at the point indicated at 45 and having one end engaging the under side of the rocker arm 43. The opposite end of the lever 44 constantly engages the periphery of a cam 46 fixed to a shaft 47 journaled in bearings 48. This shaft 47 is adapted to be actuated by a pulley 49 about which is trained a belt 50, and the latter is adapted to be connected to any suitable source of power (not shown). The shaft 47 is formed intermediate its ends with a crank 51 to which is connected a rod 52 through the medium of a yoke 53. As illustrated to advantage in Figure 3, the rod 52 is pivotally mounted between the channel bars 38 at a point indicated at 54.

From the foregoing mechanism it will be clear that when the shaft 47 is rotated a corresponding movement is imparted to the cam 46 thereby effecting a rocking of the lever 44 and through the latter a rocking of the arm 43. As the arm 43 is keyed to the shaft 41, it will be clear that an oscillatory movement of the latter is effected which in turn alternately lifts and lowers the rocker arms 39 to cause corresponding movement of the several rakes within the cells 36. Simultaneously with the vertical movement of the rakes, the crank 51 actuates the rod 52 to effect reciprocation of the rakes. This movement in conjunction with the vertical movement of the rakes constitutes which may be termed a curvilinear movement as the rakes substantially describe the path of an ellipse. In practice, the mechanism operates in such a manner that the several angle bars 37 move forwardly or to the left as when viewed in Figure 6 when in lowered position, and rearwardly or to the right when in elevated position, the lowering and elevating of the rakes occurring at the extremities of their horizontal movements.

As shown in Figures 2 and 5, the outer side wall of each cell is formed with an outlet port 55 which effects communication between the cell and a launder 56 which is arranged on an incline at one side of the tank as clearly shown in Figure 1 so as to underlie all of the ports. Each port is controlled by a shut-off 57 slidably mounted in guideways 58.

In the operation of the jig, crushed rock or any other material to be treated is fed into the first cell to the right as when viewed in Figure 6. This cell has been previously filled with water and bedded in the usual manner. As the material accumulates on the screen 35, it encounters the angle bars 37 of the corresponding rake, the latter being

in lowered position and moving from right to left. With water supplied to the several compartments of the plunger section 16, and the plungers operating to effect a pulsation of the water in the compartments of the separating section, the ore within the cell above referred to works down to the bottom of the cell, the fines pass through the screen and being finally drawn off through the faucet 20 while the cherts and coarse ore are drawn off through the corresponding outlet port 55. The rock in the material works to the top of the cell and during the movement of the rake to the left is moved toward and finally into the next cell in advance. This operation is repeated throughout the several cells of the jig until finally the tailings are discharged into a compartment indicated at 59 at the forward end of the tank where they are subsequently collected. The fines which percolate the screens of the cells gravitate to the bottom of the compartments where they are subsequently collected by opening of the faucets. The cherts and coarse ore is discharged through the ports 55 into the launder 56.

By a consideration of the foregoing operation it will be manifest that the jig operates to convey the material from cell to cell by mechanical means only, thus rendering the action positive and eliminating the use of hydraulic power or gravity. It is to be particularly noted that the several rakes are in effect hingedly mounted to permit of their being folded back or raised during the operation of spudding.

Although I have herein shown and described only one form of jig embodying my invention, it is to be understood that various changes and modifications may be made herein without departing from the spirit of the invention or the spirit and scope of the appended claims.

What I claim is:

1. In an ore jig, a tank divided into a plurality of cells having screened bottoms, a plurality of rakes, one for each of the cells, means for supporting the rakes for curvilinear movements comprising yokes, a shaft, rocker arms fixed to the shaft and having sliding contact with said yokes, means for oscillating said shaft whereby said rocker arms are lifted and lowered to effect a vertical movement of the several rakes, and means for reciprocating the rakes in such manner that the two motions occur alternately with respect to the upward and downward movements of the rocker arms.

2. In an ore jig, a tank divided into a plurality of cells having screened bottoms, a plurality of rakes, one for each of the cells, means for supporting the rakes for curvilinear movements comprising yokes, a shaft, rocker arms fixed to the shaft and having sliding contact with said yokes,

- means for oscillating said shaft whereby said rocker arms are lifted and lowered to effect a vertical movement of the several rakes, a rotatable shaft, a cam fixed to the 5 rotatable shaft, a rocker arm fixed to the oscillatory shaft, a lever operatively connecting the cam and last mentioned rocker arm to effect an oscillation of the first shaft when the second shaft is rotated whereby 10 upward and downward movements of said rakes is effected, a crank formed on the rotatable shaft, and a rod connecting said crank with said rakes to effect reciprocation of the rakes when the shaft is rotated.
- 15 3. In an ore jig, a tank divided into a plurality of cells having screened bottoms, rakes movable within the cells and comprising perforated angle bars, channel bars rigidly connecting all of the angle bars, yokes 20 secured to the channel bars, an oscillatory shaft, rocker arms fixed to said shaft and slidably engaging said yoke, means for oscillating said shaft whereby upward and downward movement of the angle and channel bars is effected, and means for reciprocating the angle bars to effect horizontal 25 movement of the angle bars.
4. A transfer means of the character described, comprising an elongated rake, a 30 shaft parallel thereto, arms extending rigidly from the shaft, connecting means between each arm and rake adapted to permit raising and lowering of the rake with the 35 rocking movement of the shaft and also adapted to permit longitudinal reciprocating movement of the rake, means whereby the shaft will be rocked to raise and lower the rake, and means for reciprocating the rake, said rocking movement of the shaft for raising and lowering the rake and said reciprocating movement of the rake occurring at 40 such intervals as to give the rake a transferring action in one direction.
5. A transfer means of the character described, comprising an elongated rake, a 45 shaft parallel thereto, arms extending rigidly from the shaft, connecting means between each arm and rake adapted to permit raising and lowering of the rake with the 50 rocking movement of the shaft and also adapted to permit longitudinal reciprocating movement of the rake, means whereby the shaft will be rocked to raise and lower the rake, and means for reciprocating the rake, said rocking movement of the shaft for raising and lowering the rake and said reciprocating movement of the rake occurring at 55 such intervals as to give the rake a transferring action in one direction, and means for adjustably raising or lowering said arms 60 and thereby to regulate the transferring action of said rake.

FRED DE MIER.
